UNITED STATES PATENT OFFICE.

FRANK B. COOK, OF CHICAGO, ILLINOIS, ASSIGNOR TO FRANK B. COOK COMPANY, OF CHICAGO, ILLINOIS, A CORPORATION OF ILLINOIS.

ELECTRIC SWITCH.

1,193,239.

Specification of Letters Patent. Patented Aug. 1, 1916.

Application filed January 15, 1915. Serial No. 2,422.

To all whom it may concern:

Be it known that I, FRANK B. COOK, citizen of the United States, residing at Chicago, in the county of Cook and State of Illinois, have invented a certain new and useful Improvement in Electric Switches, of which the following is a full, clear, concise, and exact description, reference being had to the accompanying drawings, forming a part of this specification.

My invention relates to electric switches employing complementary parts in the form of spring jacks and conducting plugs.

The invention has for one of its objects such a construction of these two complementary parts of a switch that the thimbles or other third spring jack contacts at the front thereof will not be adapted to have simultaneous engagement with any two contacts of the plug whereby the plug contacts will be limited to engagement with the contacts of the jack to which the plug contacts are complementary.

The invention has for another of its objects the improved formation of spring jacks and for another of its objects the improved formation of spring jack engaging plugs, all as will clearly appear from the following description and claims.

I will explain my invention more fully by reference to the accompanying drawings showing the preferred embodiment thereof and in which—

Figure 1 is a view with the plug portion of the switch in elevation and a part of the jack, which coöperates with the plug, in section; Fig. 2 is a sectional view on line 2-2 of Fig. 1; Fig. 3 is a sectional view on line 3-3 of Fig. 2; Fig. 4 is a sectional view on line 4-4 of Fig. 2; Fig. 5 is a sectional view on line 5-5 of Fig. 2; Fig. 6 is a plan view, on a smaller scale, of a small group of jacks; Fig. 7 is a view of a part of the structure of Fig. 6; Fig. 8 is a sectional view on line 8-8 of Fig. 6; Fig. 9 is a sectional view on line 9-9 of Fig. 6; Fig. 10 is a view on line 10-10 of Fig. 6; Fig. 11 is a sectional view on line 11-11 of Fig. 7; Fig. 12 is a perspective view of a current conducting portion of the structure; and Fig. 13 is a perspective view illustrating one of the jack contact springs.

Like parts are indicated by similar char-

acters of reference throughout the different figures.

A strip 1 of insulation of a length corresponding to the number of spring jacks to be mounted is provided with a front rail 2 in which the thimbles 3 or other third jack contacts are disposed, the bores of the thimbles snugly receiving the forward continuation of the plug or third contact portion 4. The end portions of the strip 1 are desirably of the same height and are alined with the rail 2. The portion of the strip to the rear of the rail and between the ends thereof is preferably thinner than the rail and is desirably disposed intermediate the top and bottom planes of the rail. This intermediate portion of the strip is provided with recesses 5 which are alined with the axes of the thimbles 3, these recesses extending from the rail 2 sufficiently to the rear to receive plugs when inserted to the fullest extent within the corresponding jacks. The strip 1, in the process of manufacture, originally carries only the thimbles 3 and the conductors 6 extending rearwardly from these thimbles, the forward ends of the conductors 6 being of bifurcated or fork-shaped formation with branches that correspond generally in shape to the openings 5 and the forward ends of which branches are engaged to have extended soldered, brazed or welded connection with their thimbles as indicated in Figs. 2 and 12. Thus each thimble is interposed between and is electrically connected with the two forward branches of its conductor 6. All parts of each conductor 6, excepting its rear end, including its bifurcations and together with the thimbles 3 are preferably molded within the mounting strip 1 and its forward portion 2.

The talking contact springs 7 and 8 are mounted upon the top and bottom sides of the strip 1 at the rear end thereof and normally rest upon projections 9, 10, the projections 9 being separated longitudinally of the strip as are the projections 10 to reduce leakage between springs of adjacent jacks, these projections or ridges 9 and 10 upon each side of the strip being also desirably separated widthwise of the strip to reduce the amount of insulating material required. Said projections are preferably integrally formed with the strip of insulating material

1 that carries them. The forward ridges or projections 10 also constitute back stops against which the springs 7 and 8 are forced by their own resilience and which limit the 5 extent to which these springs may approach each other. I desirably form the jack structure by suitably positioning the springs 7 and 8 within a molding machine with their openings 11 in alignment with previously 10 formed openings 12 at the rear of the strip 1, through which openings molding material is forced when it is operated upon by the molding machine to form the top and bottom binding strips 13, between which and 15 the strip 1 the rear ends of the contact springs 7 and 8 are disposed. Thus these springs 7 and 8 are held upon the rear of the contact strip 1 by the strips 13 by means of bridge connections or rivet portions 14 that 20 pass through the openings 11 in the springs 7 and 8 and through correspondingly positioned openings 12 at the rear of the strip 1. The strips 13, in extending longitudinally of the strip 1, are connected as frequently 25 by the bridge portions 14 as there are openings 11 and corresponding openings 12 in the strip 1 whereby the strips 13 are held in intimate clamping engagement with the contact springs. In other words 30 each strip 13 constitutes a composite rivet head common to a plurality of rivet shanks 14 that pass through aligned openings 11 and 12. The rear of the strip 1 is provided with shallow grooves 15 in the top and bottom 35 of the strip and whose longitudinal borders are engaged by the springs 7 and 8 and between which borders the holes 12 are disposed, these channels serving to receive a part of the molding material of which the 40 strips 13 are made whereby these strips are prevented from moving crosswise of the main strip 1 in the event that the bridge portions 14 should not be sufficiently effective in preventing all relative movement between 45 the strips 13 and 1. The grooves 15 are desirably rectangular in formation so that the parts of the strip 13 received therein will be so engaged thereby as to be unresponsive to turning effort arising when 50 the springs 7 and 8 are spread apart by inserted plugs. While I prefer to mount the conductor 6 within the strip 1 in the manner described I do not wish to be limited to such a disposition of these conductors in all 55 embodiments of the invention.

The forward rail 2 of the strip 1 constitutes a face portion of a switch board structure and projects sufficiently forward of the third jack contacts 3 to prevent these third 60 jack contacts from directly connecting any contact portions of the plug that is in the process of insertion, the holes in the strip rail 2 which receives the thimbles being desirably contracted at the front face of the 65 rail to equal the bores of the thimbles in

diameter. The result is that no angular position of a plug with respect to a jack can be imparted that will permit the thimble of the jack to have simultaneous engagement with any two contact portions of the plug. The 70 plug illustrated includes, in addition to the heel contact 4, the tip 16 and a ring 17 preferably scalloped which are adapted respectively for engagement with the switch springs 7 and 8 of a jack when a plug having these parts is fully inserted. These plug contact portions are so related with respect to each other and with respect to the strip rail 2 and thimbles 3 that said thimbles are incapable of having simultaneous connection 75 with any two plug contacts.

The contact portion 4 is generally tubular but is desirably cut away at an intermediate portion to afford access to its interior at points where connections are to be made 80 with the contacting or other strands of the cord circuit of which the plug forms a part. The forward end of the bore of the tubular conductor 4 is filled with insulation 18 which is continued rearwardly of the points of attachment of the aforesaid cord strands where the filling of insulating material may support short threaded nuts 19 and 20 into which binding screws 21 may be threaded 85 to clamp the cord conductors 22 in place, 90 the third conducting cord being electrically connected with the heel contact 4 in a well known manner. The terminal nuts 19 and 20 are respectively connected with the ring 95 17 and tip 16 by means of conductors 23 and 24 which are soldered or otherwise have connection with the ring and tip. The molding insulating material is forced into the space 100 in the tubular element 4 in which the conductors 23 and 24 are previously disposed and in order to prevent the flowing insulating material from bringing these conductors into direct contact with each other or with other metallic portions of the plug that 105 should be insulated therefrom I employ insulation about the conductors 23, 24 which is preferably in the form of enamel but which may be of other form if desired, and while these insulated conductors are preferably 110 separately formed from the plug contacts to which they extend I do not wish to be limited to this characteristic since the insulation thereof not only enables me to practise the method of my latter copending application 115 but prevents undesirable contact of these conductors in the event of injury or deterioration.

While I have shown a spring jack having three contact portions and a plug having three complementary contact portions I do 120 not wish to be limited to the number of contact portions employed in these complementary elements of my improved switch structure.

Claims relating to the plug are included 125

in my co-pending application Serial No. 103,102, filed June 12, 1916.

Having thus described my invention I claim as new and desire to secure by Letters Patent the following:—

1. A spring jack structure including a mounting strip of insulation having a plurality of plug receiving openings at its forward portion and provided with openings therethrough located along the mounting strip; contact springs supported by the mounting strip; and a fastening strip of insulation for holding the springs and mounting strip together, said fastening strip having integral continuations thereof which pass through the aforesaid openings in the mounting strip to secure the assembly of said strips.

2. A spring jack structure including a mounting strip of insulation having a plurality of plug receiving openings at its forward portion and provided with openings therethrough located along the mounting strip; contact springs supported by the mounting strip upon each side thereof; and a fastening strip of insulation upon each side of the mounting strip for holding the springs and mounting strip together, said fastening strips having continuations each integral with both fastening strips and which pass through the aforesaid openings in the mounting strip to secure the assembly of said strips.

3. A spring jack structure including a mounting strip of insulation having a plurality of plug receiving openings at its forward portion and provided with openings therethrough located along the mounting strip; contact springs supported by the mounting strip; and a fastening strip of insulation for holding the springs and mounting strip together, said fastening strip having integral continuations thereof which pass through the aforesaid openings in the mounting strip to secure the assembly of said strips, the contact springs having openings in alignment with the aforesaid openings in the mounting strip through which the aforesaid continuations also pass.

4. A spring jack structure including a mounting strip of insulation having a plurality of plug receiving openings at its forward portion and provided with openings therethrough located along the mounting strip; contact springs supported by the mounting strip upon each side thereof; and a fastening strip of insulation upon each side of the mounting strip for holding the springs and mounting strip together, said fastening strips having continuations each integral with both fastening strips and which pass through the aforesaid openings in the mounting strip to secure the assembly of said strips, the contact springs having openings in alignment with the aforesaid

openings in the mounting strip through which the aforesaid continuations also pass.

5. A spring jack structure including a mounting strip of insulation having a plurality of plug receiving openings at its forward portion and provided with openings therethrough located along the mounting strip; contact springs supported by the mounting strip; and a fastening strip of insulation for holding the springs and mounting strip together, said fastening strip having integral continuations thereof which pass through the aforesaid openings in the mounting strip to secure the assembly of said strips, the mounting strip being angularly channeled longitudinally thereof where the aforesaid openings therein are provided also to receive the material of the fastening strip.

6. A spring jack structure including a mounting strip of insulation having a plurality of plug receiving openings at its forward portion and provided with openings therethrough located along the mounting strip; contact springs supported by the mounting strip upon each side thereof; and a fastening strip of insulation upon each side of the mounting strip for holding the springs and mounting strip together, said fastening strips having continuations integral with both fastening strips and which pass through the aforesaid openings in the mounting strip to secure the assembly of said strips, the mounting strip being angularly channeled longitudinally thereof where the aforesaid openings therein are provided also to receive the material of the fastening strips.

7. A spring jack structure including a mounting strip of insulation having a plurality of plug receiving openings at its forward portion and provided with openings therethrough located along the mounting strip; contact springs supported by the mounting strip; and a fastening strip of insulation for holding the springs and mounting strip together, said fastening strip having integral continuations thereof which pass through the aforesaid openings in the mounting strip to secure the assembly of said strips, the contact springs having openings in alignment with the aforesaid openings in the mounting strip through which the aforesaid continuations also pass, the mounting strip being angularly channeled longitudinally thereof where the aforesaid openings therein are provided also to receive the material of the fastening strip.

8. A spring jack structure including a mounting strip of insulation having a plurality of plug receiving openings at its forward portion and provided with openings therethrough located along the mounting strip; contact springs supported by the mounting strip upon each side thereof; and

- a fastening strip of insulation upon each side of the mounting strip for holding the springs and mounting strip together, said fastening strips having continuations each integral with both fastening strips and which pass through the aforesaid openings in the mounting strip to secure the assembly of said strips, the contact springs having openings in alinement with the aforesaid 10 openings in the mounting strip through which the aforesaid continuations also pass, the mounting strip being angularly chan- neled longitudinally thereof where the aforesaid openings therein are provided also to receive the material of the fastening strips.
- In witness whereof, I hereunto subscribe my name this ninth day of January, A. D. 1915.
